UNITED STATES PATENT OFFICE

JOHN BUCHMANN, OF HAMILTON, OHIO

BRUSH

Application filed May 8, 1930. Serial No. 450,790.

This invention relates to brushes and has particular relation to those brushes having tufts of bristles which can be readily replaced when they become worn or broken.

5 In the construction of brushes having tufts which may be replaced, it is necessary to so construct the parts that when a new set of tufts is being placed, it will not be difficult to assemble the parts in their proper 10 places.

The primary object of this invention is the provision of an improved brush having bristle tufts which may be readily replaced when the bristles become broken or worn.

15 Another object of the invention is the provision of an improved brush wherein the bristles are held in place by a securing means covering a plurality of rows of bristle tufts.

Another and still further object of the 20 invention is to provide a brush having bristle tufts which may be separately replaced, the bristles being held in place between two plate members.

Another and still further object of the 25 invention is to provide a brush having bristle tufts with holders having flanges which are held between two plate members, thereby holding the bristle tufts in proper position relative to each other.

30 Other and further objects will be apparent to those skilled in the art from a reading of the complete specification and claims.

Referring to the drawing wherein I have 35 illustrated an embodiment of my invention as applied to a coating brush for use in paper manufacture,

Figure 1 is a cross section of my invention taken as indicated by the line 1—1 of 40 Figure 4.

Figure 2 is a view of the parts of Figure 1, but showing the members separated and in position to be assembled.

45 Figure 3 is a detail view showing a modified construction wherein no opening in the back member is necessary, the tuft holding ferrule being received by the securing plate member.

Figure 4 is a plan view of the holding member through which the bristles extend.

50 Figure 5 is a side view of my invention.

Throughout the specification and claims the same reference characters refer to the same or similar parts.

Referring particularly to Figures 1 and 2, the numeral 10 designates the main body 55 or back member of the illustrated brush made according to my invention. In this member 10, I provide openings 11 into which the tuft holding ferrules 12 are located when in operative position. The tuft holding ferrules 12 are provided with outward extending means as the flanges 12^a. The bristle tufts 13 are inserted in the tuft holders 12 and are secured in any suitable or well known manner. 60

The construction of the tuft itself may be in accordance with any suitable or well known practice. The tufts of hair or bristles may be held together by setting the ends in cement or pitch or vulcanized in rubber. The tuft may 70 be set or cemented in the ferrule 12, the latter being made of tin, brass, iron, steel, aluminum or other metal or the ferrule may be made of vulcanized rubber, holding the bristles or hairs directly, the flanges being integral 75 therewith.

Securing means 14 is provided to hold the tufts in place against the back member 10. In the embodiment illustrated the securing means 14 is constructed as a flat plate. Openings 15 are provided through which the tufts of bristles or hairs pass. The back 10 and the member 14 are secured together in any suitable or well known manner as by the bolts 16. When assembled, the bodies of the ferrules 12 85 are in the openings 11 and the flanges 12^a are held between the adjacent faces of the back 10 and the holding means 14.

In the modified form shown in Figure 3, the flanges 112^a are at the outer end of the 90 ferrule tuft holding means 112 which holds the hairs or bristles 113. The flange 112^a is held in place between adjacent faces of the back member 110 and the holding means 114.

In this construction, the openings 115 are 95 large enough to accommodate the body of the ferrule tuft holding means 112.

In this construction attention is called to the fact that the necessity of making the holes as at 11 is avoided and it is not as important 100

to operation that exactitude in the location of the openings 115, be observed. In the embodiment illustrated in Figures 1 and 2, it is necessary to have the axes of corresponding holes and openings substantially coincident with each other.

The parts 10, 14, 110, 114 may be made of any suitable metal or wood or of compositions such as bakelite, hard rubber, celluloid, 10 formica, etc. Since each tuft and its holder is separate, much warping, shrinking and expansion or contraction may take place without destroying the efficient operation.

While I have shown and described embodiments of my invention in detail, I desire to have it understood that the disclosure is merely illustrative and that modifications and changes may be made without departing from the spirit of the invention and within the 20 scope of the appended claims.

Having described my invention, what I claim and desire to secure by Letters Patent is:

1. A brush construction comprising replaceable bristle tufts, a back member, a tuft holder on the end of each tuft, flanges on the tuft holders, a member secured to the back member and in position to hold the flanges in place relative to the back member, the second member being provided with openings to permit the passage of the bristles.

2. A brush construction comprising replaceable bristle tufts, a back member, a tuft holder on the end of each tuft, flanges on the tuft holders, a member secured to the back member and having openings to receive the tuft holders when in place, the flanges being held between the two members when the parts are in place.

3. A brush construction comprising replaceable bristle tufts, a back member, a tuft holder on the end of each tuft, flanges on the tuft holders, a member secured to the back member and having openings from which the bristles extend, the back member having openings to receive the tuft holders, the flanges being held between the two members when the parts are in place.

In testimony whereof I hereunto affix my signature.

JOHN BUCHMANN.
